SHIRT FOLDING DEVICE

Caesar A. Calder, Verona, N. J.

Application June 13, 1950, Serial No. 167,748

15 Claims. (Cl. 223—37)

1

This invention relates to shirt folding devices. An object of this invention is to provide a shirt folding device on which a sport shirt with short or long sleeves or any other shirt may be folded, with the use of an ordinary shirt board with either two ordinary shirt bands or a bag, and without putting creases in the pockets or close to the front opening of the shirt. With the ordinary shirt folding device the shirt is folded about a shirt board which extends lengthwise of the shirt. In other words, when the shirt is folded as heretofore about such boards, it is longer than it is wide, and due to that fact the creases on the shirt are on opposite sides of and close to the middle of the shirt. This is so, since the shirt board is about 8" in width. The creases on the shirt folded lengthwise on the shirt board usually come out where the pockets are located. This is particularly true in the case of sport shirts, and when such shirt is opened up and worn, the creases can be seen in the pockets, which is unsightly.

In accordance with the present invention the shirt folding machine is adapted to fold the shirt wider from side to side than from front to rear. In other words, the shirt is folded about the shirt board placed crosswise instead of lengthwise. The long dimension of the shirt board is from side to side, whereas the short dimension is from bottom to top. When the shirt is folded about a board in such condition, the side creases are way beyond the pockets so that there are no creases on the pockets.

Another object of this invention is to provide a highly improved shirt folding device which may be applied to existing shirt folding tables and yet not interfere with standard or previous shirt folding practice.

Still another object of this invention is to provide a highly improved shirt folding device of the character described having improved means to permit the shirt to be folded wider than under present practice, and which will permit the shirt to be readily removed after it is folded.

Yet another object of this invention is to provide a highly improved, strong, durable and rugged shirt folding machine of the character described which shall be relatively inexpensive to manufacture, easy to assemble and manipulate, and which shall yet be practical and efficient to a high degree in use.

Other objects of this invention will in part be obvious and in part hereinafter pointed out.

The invention accordingly consists in the features of construction, combination of elements, and arrangement of parts, which will be exemplified in the construction hereinafter described,

2

and of which the scope of invention will be indicated in the following claims:

In the accompanying drawings in which is shown various illustrative embodiments of this invention,

5 Fig. 1 is a top plan view of a shirt folding machine embodying the invention;

Fig. 2 is a side elevational view thereof;

Fig. 3 is an opposite side elevational view there-
10 of;

Fig. 4 is a cross-sectional view taken on line
4—4 of Fig. 1;

Fig. 5 is a cross-sectional view taken on line
5—5 of Fig. 1;

15 Fig. 6 is a view similar to Fig. 5 but showing the folding leaf in raised position;

Fig. 7 is a partial side elevational view of the device showing the inner and outer rods in clamp-
ing position;

20 Fig. 8 is a view similar to Fig. 7 but showing the position of the apparatus when the shirt is clamped, but raised up to permit the shirt to be removed;

Fig. 9 is a cross-sectional view taken on line
25 9—9 of Fig. 1;

Fig. 10 is a cross-sectional view taken on line
10—10 of Fig. 9;

Fig. 11 is a cross-sectional view taken on line
11—11 of Fig. 1;

30 Fig. 12 is a cross-sectional view taken on line
12—12 of Fig. 5;

Fig. 13 is a partial side elevational view of the device with the handle turned back as shown in
Fig. 7;

35 Fig. 14 is a cross-sectional view taken on line
14—14 of Fig. 13;

Fig. 15 is a perspective view of the device show-
ing the shirt to be folded on the table with the
outer arms down and the collar of the shirt
clamped to the leaf, and a shirt folding board
on the shirt, thereby illustrating a step in the
process of folding the shirt with the device em-
bodying the invention;

Fig. 16 is a perspective view illustrating a fur-
ther step in the folding of the shirt;

45 Fig. 17 is a view similar to Fig. 16 and illustrating
a still further step in the folding of the shirt;

Fig. 18 is a top plan view of the folded shirt held
in folded position by a pair of shirt bands;

50 Fig. 19 is a view similar to Fig. 18 but showing
the shirt within a bag; and

Fig. 20 is a side elevational view of a shirt
folding table provided with shirt folding appara-
tus embodying the present invention.

55 Referring now in detail to the drawing, 10
designates a shirt folding device embodying the
invention. The same comprises a base or table

11 which may be made of plywood and which may be 24" x 32" or of other suitable dimensions. Attached to the top face of the table 11 is a sheet metal supporting plate 12. The plate 12 comprises a rear portion 13 from which extend forwardly a pair of side portions 14 and 15. The rear edge 16 of the plate 12 may be located adjacent the rear edge 11a of the table 11. The portion 14 may be wider than the portion 15, said portions 14 and 15 being spaced apart. The plate 12 may be attached to the board by screws 17 or in any other suitable manner.

Fixed to the top of the plate 12 are a pair of parallel bearing members 20. Each bearing member 20 comprises a bottom block 21 and a top block 22 screwed thereto and to the plate 12 and table 11, by means of screws 23 passing through suitable registering openings 24 in said blocks. Each pair of blocks may be pinned together by a pin 25. Each pair of blocks 21, 22 are formed with registering notches 21a, 22a at their meeting faces forming bearing openings for the purpose hereinafter appearing. It will be noted that one bearing member is on portion 14 and the other on portion 15 of plate 12. They are parallel to one another and in alignment with each other. Bearing openings 21a, 22a are coaxial. Extending through said bearing openings 21a, 22a is a tube 26 which is rotatably mounted in horizontal position. The ends of the tube project beyond the bearing blocks 20. Fixed to each of the projecting ends of the tube 26 is a collar 27. Each collar 27 may be fixed to the tube by means of a set screw 28. Welded or screwed or otherwise fixed to each collar is an inner clamping arm 29. Each arm 29 comprises an inner portion 30 extending radially from the collar 27, an inclined offset portion 31 extending from portion 30, and an outer end portion 32 parallel to the portion 30. When the portions 32 contact the upper face of the table 11, the portions 30 are disposed in spaced parallel relationship above the plate 12.

It will now be understood that arms 29 and tube 26 are fixed for rotation together as a unit and constitute an inner clamping member which will be designated by numeral 33. The arms 32 may be swung from the down position where the portions 32 contact the base or table 11, upwardly through an angle of somewhat more than 90° so as to be inclined upwardly and rearwardly. A radial pin 34 fixed to one of the collars 27 will serve to retain the inner clamping member 33 in raised position.

Fixed to the table 11 and disposed between portions 14 and 15 of plate 12 are a pair of hinge members 35. Each hinge member 35 comprises a hinge leaf 36 bolted, screwed or otherwise attached to the table by fastening members 37 and leaves 38 hinged about suitable hinge pins to the leaves 36. Attached to the leaves 38 is a panel 40. The panel 40 is substantially rectangular in shape. It is of greater dimension from front to rear than sideways. It may be 8" wide and 12", 14" or 16" long. Said panel 40 may be made of sheet metal or other suitable material. It has side edges 41, a front edge 42, and a rear edge 43. The rear edge 43 is spaced forwardly of the tube 26.

Fixed to the top of the table or base 11 and disposed between the hinges 35 and also between the panel 40 and the tube 26 is a bracket 44. The bracket 44 comprises a pair of outwardly extending apertured feet or ears 45 contacting the top of the table 11 and attached thereto by 70

means of screws 46 passing through the apertures. Extending upwardly from the feet are side walls 47 interconnected by a rear transversely curved wall 48. The side walls 47 are 5 formed with a pair of aligned through openings 49 and also with a pair of inwardly extending hollow pintles 50. Extending through the openings 49 is a transverse pin or rivet 51 fixed to the bracket. Pivoted to the pintles 50 is clamp member 52 having side walls 53 interconnected by a longitudinally and transversely curved wall 54. The walls 53 are formed with bearing openings 55 through which the pintles 50 pass. The clamp member 52 is formed at its rear end with a pair of downwardly extending apertured ears 56 10 carrying a transverse pin 57. Said clamp member is also formed at its forward end with a pair of downwardly extending apertured ears 58 carrying a transverse pin 59. Interconnecting 15 the transverse pin 51 with a lug or prong 60 stamped from the top wall 54 is a coil tension spring 61.

It will be noted that the transverse rivet pin 51 is disposed below the pintles 50. When the clamp member 52 is swung downwardly the spring 61 is on one side of the pintles 50 to retain the clamp member in its down position. This position is illustrated in Fig. 5 of the drawing. However, should the clamp member be 20 raised to the position shown in Fig. 6, the spring 61 is shifted to the opposite side of the pintles 50, to retain the clamp in the up position. The clamp is thus maintained either in its down or up positions. In the up position the wall 54 contacts the upper edge 48a of wall 48, as shown in Fig. 6.

Fixed to the transverse pins 57, 59 is a shirt clamping member 63. Member 63 comprises a member 64 having a portion 65 contacting the 40 undersides of the pins 57, 59, a portion 66 looped about pin 57, a portion 67 parallel to portion 65 and contacting pin 59 and riveted by rivet 68 to portion 65. Extending from portion 67 is an S-shaped hook portion 70 serving as a handle 45 for pulling the clamp member up and down. Riveted between the portions 65 and 67 is a tongue 71 which extends forwardly beyond portion 65. It will now be understood that members 63 and 52 are fixed together and swing together 50 about the axis of the pintles 50. The tongue 71 overlies the longitudinal mid-portion of the panel 40 and extends somewhat more than one-half the length of said panel.

Fixed to one side edge 41 of the panel, adjacent the rear edge 43 is a latch member 75. Latch member 75 comprises a block 76 formed with a slot 77 to receive an edge portion of the panel 40. The block may be fixed to the panel 40 by a set screw 78 passing through the opening 79 in the block 76. The block 76 is formed with a longitudinally drilled opening 80 terminating short of the front end of the block. At the front end there is a reduced opening 81 coaxial with the opening 80. The rear end of the opening 80 is closed by a plug 82. Slidable on the block 76 is a latch member 83 having a head 84 within the opening 80 and a shank 85 passing through the opening 81. The forward end of the stem or reduced portion 85 is beveled upwardly and rearwardly as shown at 86. Interposed between the head 84 and the plug 82 is a coil compression spring 87. The spring 87 thus normally projects the latch member 83 forwardly for the purpose hereinafter appearing.

Extending through the tube 26 is a shaft 80.

Shaft 90 can rotate relative to the tube and also relative to the bearing blocks 20. The outer ends of the rod or shaft 90 project beyond the outer ends of the tube. Fixed to the projecting ends of the shaft 90 by set screws 91a and 92a, 5 are collars 91 and 92. Fixed to the collar 92 is an outer clamping arm 93 substantially similar to the clamping arm 29 and adapted to be aligned therewith. Fixed to the other collar 91 is an outer clamping arm 94 of somewhat different shape. The arm 94 comprises a portion 95 extending radially of the collar 91 and inclined forwardly and upwardly when said arm is in its down position, as shown in Fig. 2, of the drawing.

Extending from portion 95 is a portion 96 inclined downwardly and forwardly, and extending therefrom is a portion 97 which lies substantially flat on the table 11. Extending from the arm 84 at the junction of portions 96 and 97 is a horizontally offset arm 98 overlapping the panel 40. The arm 98 is so positioned that if the panel 40 is in its down position and the arm 94 is swung downwardly, said arm will contact the beveled surface 86 and push the latch 85 against the spring 87, so as to snap beneath the latch.

It will now be understood that shaft 90, collars 91, 92 and arms 93, 94 together form what may be termed an outer clamping member 100. The outer clamping member likewise may swing from a horizontal position, upwardly to a rearwardly and upwardly inclined position, in which position the arm 98 contacts one of the arms 29 to limit rearward swinging movement of member 100. It will be noted that when both the inner and outer clamping members 33 and 100 are in their down position, the arm 98 is located beneath the adjacent arm 29, so that if the outer clamping member 100 were raised, the inner clamping member 33 would be raised therewith, due to the engagement of arm 98 with arm 29.

Means is provided to raise the outer clamping member 100, for the purpose hereinafter appearing. To this end there is fixed to plate portion 14 and to the table 11 a bearing member 101. Said member 101 comprises a bottom block 102 attached to plate portion 14 and to the table 11 by means of screws or bolts 103. The block 102 is formed at its upper surface with a transverse semi-cylindrical groove 104. Attached to the top of block 102 by means of screws 105 is a top block 106. The top block 106 is formed with a groove 107, complementary to the groove 104 and forming therewith a through bearing opening 108. Clamped to the plate portion 14 by the bearing member 101 is a spring member 110. The spring member 110 has a flat plate portion 111 disposed beneath member 102 and formed with opening through which the bolts 103 pass. Extending upwardly from the bottom wall 101 is a curved bent back portion 113 from which extends rearwardly a free spring arm 114.

Journalled within the bearing opening 108 is a lifting crank member 115. Lifting member 115 comprises an axle portion 116 passing through the opening 108. Extending from one end of the axle portion 116 is an offset portion 120 from which extends a finger 121 engaged beneath portion 95 of clamping member 94. When the handle 118 is swung back the finger 121 rests on plate portion 114. When the handle 118 is swung forwardly the finger 121 engages the arm 94 and raises the outer clamping member 100, which in turn raises the clamping member 33.

Fixed to the axle 116 is a transverse pin 122 comprising one pin portion 123 projecting in one

direction and another pin portion 124 projecting in a diametrically opposite direction. When the handle 118 is swung in a clockwise direction, looking at Fig. 13, to raise the clamping members 33, 100, the pin portion 123 depresses the spring portion 114. Should the clamping members 33, 100 be lifted out of contact with the finger 121, the spring 114 will then automatically swing the handle backward. Rotation of the handle in a clockwise direction, looking at Fig. 13, is limited by engagement of the pin 124 with a fixed pin 125, projecting from the block 106.

The operation of the device for folding a shirt will now be described. The handle 118 is first swung backwardly, the inner and outer clamping members are swung upwardly, the metal folding leaf 40 is swung downwardly against the table, clamping members 52, 63 are raised, the shirt S to be folded is laid down on the device in the position shown in Fig. 15. The top button of the shirt should be fastened. The shirt is laid down face downwardly with the collar aligned with a transverse line 130 marked on the top of the folding leaf 40, about 8" from the lower edge 42. It will be noted that the outer end of the tongue 71 crosses the line 130, when the clamp is swung down. The sleeves of the shirt S extent outwardly and may hang over the sides of the table 11. The clamping member 63, 63 is then swung downwardly so that the outer end of the tongue 71 clamps the collar against the metal folding leaf 40. The outer clamping member 100 is then swung downwardly so that the outer ends of the arms 93, 94 press against the shoulder portions of the shirt. At the same time arm 98 will snap beneath the latch 85 to retain the outer clamping member clamped against the shirt.

The distance between the axes of the arms 32 of the inner clamping member is about 13". These arms are disposed on opposite sides of the metal folding leaf 40 and are spaced therefrom. The distance between the axes of the outer arms 93, 94 is about 13 3/4" so that the outer ends of the arms 93, 94 lie substantially in spaced parallel relationship to the portions 32 of the arms 29, when both the clamping members are down.

A flat board B of usual construction is then laid on top of the shirt with the ends of one longitudinal edge substantially contacting the outer ends of the arms 93, 94 as shown in Fig. 15 of the drawing. It will be noted that the board B is centered on the shirt and that the board is placed transversely of the shirt instead of lengthwise. The side portions of the shirt and the sleeves are then folded inwardly around the end edges of the board B and around the arms 93, 94. It will be noted that the arms 93, 94 are located substantially at the ends of the board B. The position of the shirt with the sides and sleeves folded inwardly is illustrated in Fig. 16.

The inner clamping member 33 is then swung downwardly and its arms engage the inwardly folded shirt upwardly about the lower edge of the cardboard bringing the outer end of the tail of the shirt substantially to the collar of the shirt. The board together with the shirt folded thereon is then folded upwardly about the upper edge of the cardboard to the position shown in Fig. 17. Now the whole shirt is folded on the cardboard making a package of about 8" x 14". The handle 118 is then swung forwardly to lift the outer and inner clamps together with the folded shirt and together with the leaf. The clamps are only raised about 1 1/2" giving sufficient room beneath the shirt to permit the operator to place the

usual paper bands 131 about the folded shirt and shirt board. The raised position of the clamps and shirt is shown in Fig. 17. After the bands 131 are applied the entire folded shirt may be slipped off the folding leaf and clamps. The inner and outer clamps may then be raised together, and as that is done the arm 98 will bypass the latch 85 permitting the folding leaf 40 to drop again on to the table 11. The handle 118 will then be snapped back by the spring 114. The clamps 52, 63 may then be raised and the board is in a position to receive the next shirt.

If desired, instead of placing bands 131 on the shirt, a paper bag 132 may be slipped on to the shirt when the shirt is on the raised clamps and folding leaf. The bag may have a transparent front panel 133 and is open at one longitudinal edge to receive the folded shirt. The bag together with the shirt may then be easily slipped off the clamps and folding leaf.

It will now be understood that the device embodying the invention may be applied to the usual folding table 135 now in use. Such usual folding table is provided with a folding leaf 40 and with clamps 52, 63. The usual folding table 135 has a rearwardly and upwardly inclined upper surface 136. To adapt the folding table for folding shirts in the manner disclosed herein, the plate 12 together with the inner and outer clamping members and with the clamp lifting mechanism may be attached to the top surface 136. The latch member 75 may then be attached to the folding leaf and the device is ready for use.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. A shirt folding device comprising a table, a leaf hinged to the table, a clamp hinged to the table and adapted to be resiliently pressed against the top of the leaf, an inner clamping member pivoted to the table and having a pair of clamping arms disposed on opposite sides of the leaf, an outer clamping member pivoted to the table and having a pair of arms disposed on the outer sides of the arms of the inner clamping member, and means to latch the outer clamping member to the leaf, said latching means comprising a latch on the leaf and an arm attached to one of the arms of the outer clamping member and engaging beneath one of the arms of the inner clamping member and adapted to be engaged by the latch on the leaf.

2. A shirt folding device comprising a table, a leaf hinged to the table, a clamp hinged to the table and adapted to be resiliently pressed against the top of the leaf, an inner clamping member pivoted to the table and having a pair of clamping arms disposed on opposite sides of the leaf, an outer clamping member pivoted to the table and having a pair of arms disposed on the outer sides of the arms of the inner clamping member, and means to latch the outer clamping member to the leaf, said latching means comprising a latch on the leaf and an arm at-

tached to one of the arms of the outer clamping member and engaging beneath one of the arms of the inner clamping member and adapted to be engaged by the latch on the leaf, and means to raise the outer clamping member whereby to raise the inner clamping member therewith.

3. A shirt folding device comprising a table, a leaf hinged thereto about its upper edge, a spring clamp pivoted to the table and adapted to clamp the collar of a shirt against said folding leaf, an inner clamping member comprising a transverse portion, and a pair of arms fixed to said transverse portion, means to mount said transverse portion for rotation, an outer clamping member comprising a transverse portion and a pair of arms extending therefrom, means to mount the last named transverse portion for rotation, the arms of said outer clamping member being disposed at the outer sides of the arms of the inner clamping member, a spring latch on the leaf, and a member fixed to one of the arms of the outer clamping member and adapted to engage the latch and being disposed beneath an arm of the inner clamping member.

4. A shirt folding device comprising a table, a leaf hinged thereto about its upper edge, a spring clamp pivoted to the table and adapted to clamp the collar of a shirt against said folding leaf, an inner clamping member comprising a transverse portion, and a pair of arms fixed to said transverse portion, means to mount said transverse portion for rotation, an outer clamping member comprising a transverse portion and a pair of arms extending therefrom, means to mount the last named transverse portion for rotation, the arms of said outer clamping member being disposed at the outer sides of the arms of the inner clamping member, a spring latch on the leaf, and a member fixed to one of the arms of the outer clamping member and adapted to engage the latch and being disposed beneath an arm of the inner clamping member, a bearing block on the table, a crank pivoted to the bearing block, a handle at one end of the crank, and a finger at the other end of the crank adapted to engage one of the arms of the outer clamping member for raising the latter.

5. A shirt folding device comprising a table, a leaf hinged thereto about its upper edge, a spring clamp pivoted to the table and adapted to clamp the collar of a shirt against said folding leaf, an inner clamping member comprising a transverse portion, and a pair of arms fixed to said transverse portion, means to mount said transverse portion for rotation, an outer clamping member comprising a transverse portion and a pair of arms extending therefrom, means to mount the last named transverse portion for rotation, the arms of said outer clamping member being disposed at the outer sides of the arms of the inner clamping member, a spring latch on the leaf, and a member fixed to one of the arms of the outer clamping member and adapted to engage the latch and being disposed beneath an arm of the inner clamping member, a bearing block on the table, a crank pivoted to the bearing block, a handle at one end of the crank, and a finger at the other end of the crank adapted to engage one of the arms of the outer clamping member for raising the latter, and means to limit swinging movement of the crank in one direction.

6. A shirt folding device comprising a table, a leaf hinged thereto about its upper edge, a spring clamp pivoted to the table and adapted to clamp

the collar of a shirt against said folding leaf, an inner clamping member comprising a transverse portion, and a pair of arms fixed to said transverse portion, means to mount said transverse portion for rotation, an outer clamping member comprising a transverse portion and a pair of arms extending therefrom, means to mount the last named transverse portion for rotation, the arms of said outer clamping member being disposed at the outer sides of the arms of the inner clamping member, a spring latch on the leaf, and a member fixed to one of the arms of the outer clamping member and adapted to engage the latch and being disposed beneath an arm of the inner clamping member, a bearing block on the table, a crank pivoted to the bearing block, a handle at one end of the crank, and a finger at the other end of the crank adapted to engage one of the arms of the outer clamping member for raising the latter, means to limit swinging movement of the crank in one direction, and spring means to rotate said crank in an opposite direction.

7. A shirt folding device comprising a table, a leaf hinged thereto about its upper edge, a spring clamp pivoted to the table and adapted to clamp the collar of a shirt against said folding leaf, an inner clamping member comprising a transverse portion, and a pair of arms fixed to said transverse portion, means to mount said transverse portion for rotation, an outer clamping member comprising a transverse portion and a pair of arms extending therefrom, means to mount the last named transverse portion for rotation, the arms of said outer clamping member being disposed at the outer sides of the arms of the inner clamping member, a spring latch on the leaf, and a member fixed to one of the arms of the outer clamping member and adapted to engage the latch and being disposed beneath an arm of the inner clamping member, and means to limit upward swinging movement of the inner clamping member.

8. A device of the character described comprising a table, a leaf hinged about its rear end to the table and adapted to overlie the table, a pair of bearing blocks on the table and disposed rearwardly of the leaf, a tube rotatably mounted in the bearing blocks and projecting beyond said bearing blocks, a first pair of arms fixed to the ends of the tube, a shaft passing through said tube and rotatable thereon, and a second pair of arms attached to the ends of said shaft and disposed at the outer sides of and alongside the first pair of arms, and means on the second pair of arms to raise the first pair of arms therewith, when raising said second pair of arms.

9. A device of the character described comprising a table, a leaf hinged about its rear end to the table and adapted to overlie the table, a pair of bearing blocks on the table and disposed rearwardly of the leaf, a tube rotatably mounted in the bearing blocks and projecting beyond said bearing blocks, a first pair of arms fixed to the ends of the tube, a shaft passing through said tube and rotatable thereon, a second pair of arms attached to the ends of said shaft and disposed at the outer sides of the first pair of arms, and means to latch one of the second pair of arms to said leaf.

10. A device of the character described comprising a table, a leaf hinged about its rear end to the table and adapted to overlie the table, a pair of bearing blocks on the table and disposed

rearwardly of the leaf, a tube rotatably mounted in the bearing blocks and projecting beyond said bearing blocks, a first pair of arms fixed to the ends of the tube, a shaft passing through said tube and rotatable thereon, a second pair of arms attached to the ends of said shaft and disposed at the outer sides of the first pair of arms, and means to latch one of the second pair of arms to said leaf, said means comprising a latch on the leaf and a member on said arm of said second pair of arms engaging beneath one of the arms of the first pair of arms and engageable with said latch.

11. A device of the character described comprising a table, a leaf hinged about its rear end to the table and adapted to overlie the table, a pair of bearing blocks on the table and disposed rearwardly of the leaf, a tube rotatably mounted in the bearing blocks and projecting beyond said bearing blocks, a first pair of arms fixed to the ends of the tube, a shaft passing through said tube and rotatable thereon, a second pair of arms attached to the ends of said shaft and disposed at the outer sides of the first pair of arms, and means to latch one of the second pair of arms to said leaf, said means comprising a latch on the leaf and a member on said arm of said second pair of arms engaging beneath one of the arms of the first pair of arms and engageable with said latch, and means pivoted to the table for lifting one of the second pair of arms.

12. A device of the character described comprising a table, a leaf hinged about its rear end to the table and adapted to overlie the table, a pair of bearing blocks on the table and disposed rearwardly of the leaf, a tube rotatably mounted in the bearing blocks and projecting beyond said bearing blocks, a first pair of arms fixed to the ends of the tube, a shaft passing through said tube and rotatable thereon, a second pair of arms attached to the ends of said shaft and disposed at the outer sides of and alongside the first pair of arms, said first pair of arms being swingable upwardly independently of the second pair of arms, means on the second pair of arms to raise the first pair of arms upon raising said second pair of arms, and releasable clamping means overlying the leaf, and spring pressed against said leaf.

13. A device of the character described comprising a table, a leaf hinged about its rear end to the table and adapted to overlie the table, a pair of bearing blocks on the table and disposed rearwardly of the leaf, a tube rotatably mounted in the bearing blocks and projecting beyond said bearing blocks, a first pair of arms fixed to the ends of the tube, a shaft passing through said tube and rotatable thereon, a second pair of arms attached to the ends of said shaft and disposed at the outer sides of the first pair of arms, and means to latch one of the second pair of arms to said leaf, said means comprising a latch on the leaf and a member on said arm of said second pair of arms engaging beneath one of the arms of the first pair and engageable with said latch, means pivoted to the table for lifting one of the second pair of arms, and spring means to rotate said pivoted lifting means.

14. A shirt folding device comprising a table, a leaf hinged to the top of the table, a clamp hinged to the top of the table, means to resiliently press the clamp against the top of the leaf, an inner clamping member pivoted to the table and having a pair of clamping arms dis-

11

posed on opposite sides of the leaf, an outer clamping member pivoted to the table and having a pair of arms disposed on the outer sides of the arms of the inner clamping member, said inner clamping member being swingable upwardly from the table independently of the outer clamping member, means on the outer clamping member to swing the inner clamping member upwardly upon swinging said outer clamping member upwardly, and means to latch the outer clamping member to the leaf.

15. A shirt folding device comprising a table, a leaf hinged to the top of the table, a clamp hinged to the top of the table, means to resiliently press the clamp against the top of the leaf, an inner clamping member pivoted to the table and having a pair of clamping arms disposed on opposite sides of the leaf, an outer clamping member pivoted to the table and having a pair

5

of arms disposed on the outer sides of the arms of the inner clamping member, said inner clamping member being swingable upwardly from the table independently of the outer clamping member, means on the outer clamping member to swing the inner clamping member upwardly upon swinging said outer clamping member upwardly, means to latch the outer clamping member to the leaf, and manually operated means on the table to raise the outer clamping member.
